EMASCULATOR

Spencer W. Thomas, Trenton, Nebr.

Application January 15, 1934, Serial No. 706,722

3 Claims. (Cl. 128—306)

This invention relates to an emasculating tool or implement employed for castrating certain animals.

Needless to say the art to which the invention relates is already well developed and characterized by various types and styles of emasculators designed for accomplishing the desired results by performing a bloodless operation and to overcome distress and attendant subsequent injuries. The present invention is in the nature of a novel contribution to this line of endeavor regarded as unique and practicable in that it embodies certain features of construction and refinement calculated to permit it to better fulfill the function for which the parts are expressly designed and coordinated.

Briefly stated the preferred embodiment of the invention embodies a handle provided with an especially shaped cord abutment claw against which the cord is firmly pressed and crushed through the instrumentality of a rotary cam-like compression element swingable through a predetermined path and turnable on a movable pivot through the action of a manually controlled actuating lever.

Structurally speaking, novelty is predicated upon the special configuration and mounting of the swingable rotary crushing cam and its particular mounting and association with a companion cord holding or restraining claw.

A further feature is based upon the adoption and use of a variable actuating lever adjustable to promote the refined and sensitive crushing and locking action desired.

Other features and advantages will become more readily apparent from the following description and drawings.

In the drawings:

Figure 1 is an elevational view of the preferred embodiment of the invention showing the parts in non-clamping position.

Figure 2 is a view like Figure 1 showing the parts adjusted to the position assumed by said parts when the cords of the testicles are bound and severed.

Figure 3 is an edge view of Figure 2 observing it in a direction from right to left.

Figure 4 is a detail view of the journal used as a pivot or fulcrum for the hand adjusted actuating lever.

Figure 5 is a fragmentary detail sectional end elevational view of the forked end of said lever.

Figure 6 is a detail view of the crushing cam.

Figure 7 is a detail section on the line 7—7 of Figure 2.

Figure 8 is a detail sectional view of a concavo-convex guard washer.

Referring now to the parts by detailing reference characters and considering them in the order of prominence of size attention first comes to what may be designated as a handle 9 formed at its outer end with an integral C-shaped head 10. One terminal end 11 of the head is herein-after referred to either as a jaw or claw and it will be observed that this is gradually decreased in dimension toward its extremity and of the cross sectional shape shown in Figure 7 so as to provide a rounded abutment edge 12 against which the testical cord (not shown) is firmly clamped for severing at the time of performing the operation. Cooperable with this abutment surface 12 is a correspondingly shaped marginal portion 13 of the substantially heart-shaped crushing cam 14. This cam is a vital part of the construction and is located between the jaws 11 and 15 of the head. In fact it is confined to travel in a predetermined path, the path being governed by the attaching links 16. These links are of curved form of appropriate length and attached to the head as at 17. They are obviously disposed at opposite sides of the head and pivotally connected at their upper ends concentrically as at 18 to the cam 14.

The cam 14 is rotated and swung through its predetermined path of movement by way of a manually controlled actuating lever 19. The upper end of this lever is forked and the arms of the fork terminate in what may be distinguished as segmental ears 20. These ears straddle and are pivotally attached to the jaw 15. Also they are pivotally attached as indicated at 21 to the pendent portion of the swingable cam. This serves to bodily move and rotate the cam in the requisite progressive manner. The pivots 21 are located eccentrically to the pivot 18 so that when these pivots 21 travel to a predetermined point and the lever passes beyond the "dead center" the cam is locked in its cord crushing and binding position until voluntarily released by the attendant.

In order to regulate and adjust the activity and sensitiveness of operation of the lever 19 it is adjustably pivoted on the free end of the jaw 15. This is accomplished by the use of a journal unit of the type shown at 22 in Figure 4. Here the main journal 23 is mounted in a bearing in the jaw 15. It will be noticed that cogs 24 are splined or keyed eccentrically to the journal and at the ends of the journal are screw threaded as indicated at 25 and 26 to accommo-

date a returning nut 27 and a thumb nut 28 as shown in Figure 3. These nuts serve to hold and place the concavo-convex guard washers 29 and to keep the parts assembled. It will be noticed that the ears 20 of the fork arms have the edges of the openings formed with teeth 30 as shown in Figure 5 and these teeth surround and coat with the teeth of the cog whereby to permit the leverage to be varied and regulated by adjusting the teeth 30 with respect to the teeth of the cog. By this arrangement the proper regulatory action of the travelling rotary cam 14 is produced. The numeral 31 merely designates a stop screw which can be employed if and when desired.

With the tool occupying the position shown in Figure 1 the parts are in ineffective position ready for application and operation. The tool is sufficiently small to permit it to be practically operated with one hand. Hence by grasping the handle 9 and simultaneously grasping the lever 19 said lever can be moved toward the handle 9 in a plier-like action. In so doing the crushing cam 14 turns on its pivot 18 through the action of the pivotal connections 21. This bodily swings the cam and guiding links 16 to bring the cam into an effective clamping position. In fact it brings the edges 13 and 12 into crushing relationship against the cord and accomplishes this in a progressive rolling pressure action. Hence the cord is properly restrained, held against displacement and satisfactorily severed to accomplish the desired castrating result.

Summarizing the features of the invention it is believed that novelty will be found in these parts. First, it is thought to be new to provide a handle 9 having the C-shaped head 10 with one of the jaws 11 fashioned to provide a restraining and abutment element for the cord and for satisfactory cooperation with the travelling cam 14. Then too, the idea of using the opposed jaw 15 as a carrier and support for the adjustable actuating lever 19 is believed to be unique. The special coordination of the cam 14 with a head 10 through the instrumentality of the guiding links 16 is important. The special heart-shaped configuration of the cam 14 to provide for the progressive rolling pressure and thrust action is ingenious. The special forked construction of the lever 19 where ears 20 are formed to produce the desired travelling and rolling effect for the cam 14, as well as the regulatory mounting of the ears 20 on the jaw 15 is a mechanical refinement. All of these parts have been carefully selected and are joined to provide for smooth non-jerky action calculated to provide the operation without distress to the animal. Most of all I desire to emphasize the locking feature of the cam which guards against slippage and accidental displacement of the tool while in operation.

It is thought that persons skilled in the art to which the invention relates will be able to obtain a clear understanding of the invention after considering the description in connection with the drawings. Therefore, a more lengthy description is regarded as unnecessary.

Minor changes in shape, size, and rearrangement of details coming within the field of the invention claimed may be resorted to in actual practice, if desired.

Having thus described my invention, what I claim as new is:

1. An implement of the class described comprising a handle having a head at one end thereof, said head having a curved jaw at one end thereof, the inner edge of which is of arcuate form, an arm extending from the other end of the head, a member located between the arm and jaw and having an arcuate edge for cooperating with the arcuate edge of the jaw, a link connecting said member with the head, a handle pivoted to the arm and pivotally connected with the member for moving the member toward and away from the jaw, the arcuate edges of the jaw and member being so formed that the member first engages the outer end of the arcuate edge of the jaw and then the arcuate edge of the member approaches the arcuate edge of the jaw. 80

2. An implement of the class described comprising a handle, a substantially C-shaped head connected with one end of the handle to provide a jaw having a substantially concave inner edge and a supporting arm, a member located between the jaw and arm and having a convex edge for cooperating with the concave edge of the jaw, a link having one end pivoted to the head adjacent the base of the jaw and its other end pivoted to the member, the last mentioned pivot being substantially concentric to the convex edge, a second handle having a substantially T-shaped head, one end of which is pivoted to the free end of the supporting arm and the other end is pivoted to that end of the member which is opposite the convex edge, said convex edge and concave edge being so formed that as the member is moved to crushing 100 position by the second handle, a portion of the convex edge will first engage the outer end of the concave edge and then the convex edge of the member moves toward the concave edge of the jaw with a rolling motion. 110

3. An implement of the class described comprising a handle, a substantially C-shaped head connected with one end of the handle to provide a jaw having a substantially concave inner edge and a supporting arm, a member located between the 120 jaw and arm and having a convex edge for cooperating with the concave edge of the jaw, a link having one end pivoted to the head adjacent the base of the jaw and its other end pivoted to the member, the last mentioned pivot being substantially concentric to the convex edge, a second handle having a substantially T-shaped head, one end of which is pivoted to the free end of the supporting arm and the other end is pivoted to that end of the member which is opposite the convex 130 edge, said convex edge and concave edge being so formed that as the member is moved to crushing position by the second handle, a portion of the convex edge will first engage the outer end of the concave edge and then the convex edge of the member moves toward the concave edge of the 135 jaw with a rolling motion, the pivot which connects the second handle to the supporting arm including a pin having an eccentrically arranged toothed wheel connected therewith and said supporting arm having an opening for receiving the pin with a portion of the opening enlarged eccentrically and its wall toothed to receive the teeth of the pin. 140
